UNITED STATES PATENT OFFICE.

ISAAC LUTHER DELANEY AND JOSEPH W. PATTERSON, OF WAYNESBURG,
PENNSYLVANIA.

SEALING-MACHINE OF THE HOT-WATER TYPE.

1,142,801.

Specification of Letters Patent. Patented June 15, 1915.

Application filed February 6, 1915. Serial No. 6,642.

To all whom it may concern:

Be it known that we, ISAAC LUTHER DELANEY and JOSEPH W. PATTERSON, citizens of the United States, residing at Waynesburg, in the county of Greene and State of Pennsylvania, have invented certain new and useful Improvements in Sealing-Machines of the Hot-Water Type, of which the following is a specification.

10 This invention relates to improvements in sealing machines and more specifically to sealing machines of the hot water type.

The object of our invention is to provide a hot water sealing machine so constructed that in sealing bread, or other articles wrapped in paper to be sealed with paraffin or wax, the paper will not be scorched or burned, neither will the contents be subjected to injury.

20 A further object of our invention is to provide a machine of this character, that can be adjusted to seal packages varying in size. To this extent our machine is especially effective inasmuch as machines of 25 various sizes are not required in sealing packages of various dimensions.

A still further object of our invention is to provide a machine of this character, wherein the operator will not be subject to burns, thereby making the machine safe and harmless.

30 Other objects of this invention not at this time more particularly enumerated, will be clearly understood from the detailed description and drawings forming a part of this specification.

Furthermore, this invention consists in the novel arrangement and combination of parts more particularly described in the following specification and embodied in the claims appended hereunto and forming a part of this application.

40 Referring now to the drawings, which are merely illustrative of our invention, Figure 45 1 is a top plan view of our improved form of sealing machine. Fig. 2 is a side elevation of the same. Fig. 3 is an end elevation thereof.

50 Referring further to the drawings, where in similar reference characters designate similar parts throughout the respective views, A indicates a stationary boiler substantially L-shaped in cross section, having the short side A' vertically disposed, while 55 the long side is disposed in a horizontal

plane. An adjustable boiler B is adapted to be moved transversely across the surface of the boiler A. The boilers A and B are both provided with water supply pipes C and C' located centrally in the upper side thereof, 60 the supply pipe C being located in the upper side of the portion A' of the boiler A. The front sides of the portion A' of the boiler A, and the boiler B are rounded as at A'' and B' to facilitate the feeding of the 65 packages. To the rear of the boiler A is provided a perforated cooling plate D, having a perforated side E formed thereon. An adjustable cooling plate F of similar construction is mounted on the surface of the 70 plate D, and is adapted to slide transversely across D and in longitudinal alignment with respect to the inner side of the boiler B. For the purpose of adjustment to the plate F and the boiler B, I provide an adjusting 75 device comprising a movable plate G bent upwardly as at G'. The upturned portion G' is secured to the member to be adjusted. A plurality of supports O secured to the bottom of the boiler A and plate D are provided, on their upper sides, with lock nuts H and guide pins I, which are adapted to be placed within an elongated slot G'' in the plate G of the adjustable slides. Provision is made for the heating of the boiler 80 A by providing a burner J underneath the boiler A, said burner J having a fuel supply pipe J' attached thereto. The adjustable boiler B is provided with a lateral burner K receiving its fuel supply from the pipe J' 85 by means of the flexible tubing K'. A guard L is placed around the burner K and secured to the boiler B, thereby eliminating any possibility of the operator being burned by coming in contact with the burner K. To the 90 under side of the boiler A and the cooling plate D are secured longitudinal braces N to which are secured supporting legs M, said legs being substantially W-shaped in end elevation.

100 It will be noted that in sealing packages with wax, paraffin or any other similar material, that the boiler B and the plate F may be adjusted so as to insure a close contact thereof with the packages to be sealed.

105 The utility, adaptability, and advantages of our improved form of sealing machines being obvious, it is unnecessary to further enlarge upon the same herein.

110 Having now described and pointed out the

2
new and useful features of our invention, we do not limit ourselves to the shape of certain parts where the shape is not essential, nor do we restrict ourselves to the exact details of construction shown and described, but mean and intend to claim all equivalents and variations thereof not departing in principle from our invention and falling within the purview of the appended claims.

10. What we claim as our invention and desire to secure by Letters Patent is:

1. In a device of the kind described, in combination, a water container L-shaped in cross section, an adjustable water container 15 substantially oblong in cross section vertically mounted upon the longer arm of said L-shaped water container, a heating device mounted beneath said water containers, a perforated plate mounted adjacent one end 20 of the longer arm of said L-shaped water container and coextensive in width therewith, an upstanding flange formed upon one side of said perforated plate adjacent the shorter arm of said L-shaped water container, an adjustable perforated plate vertically disposed upon said first named plate opposite said perforated flange, means secured to said oblong water container adapted to move the same forwardly or backwardly, and a plurality of supports mounted beneath said L-shaped water container and said first named plate.

2. In a hot-water sealing machine, in combination, a horizontally disposed water container formed with an upstanding side, an upstanding movable water container adapted to seat upon said horizontally disposed water container, means secured to said upstanding movable water container adapted to secure the same in a predetermined position upon said longitudinally disposed water container, a heat dispensing device disposed adjacent the outer face of said upstanding movable water container, a heat dispensing device mounted beneath said horizontally disposed water container, a perforated plate member formed with a perforated flange on one side thereof mounted adjacent one end of said horizontally disposed water container, an upstanding perforated plate 50 movably mounted upon said first mentioned plate, adjustment means secured to said movable plate adapted to fix the same in a predetermined position, and a plurality of supports mounted beneath said horizontally disposed water container and said first mentioned plate.

In testimony whereof we affix our signatures in the presence of two witnesses.

I. LUTHER DELANEY.
JOSEPH W. PATTERSON.
